By Higdon, Longau & Higdon
Atty's:

UNITED STATES PATENT OFFICE.

ALFRED APEL, OF ST. LOUIS, MISSOURI.

DESIGN FOR A TOP.

SPECIFICATION forming part of Design No. 27,459, dated August 3, 1897.

Application filed May 24, 1897. Serial No. 637,963. Term of patent 7 years.

To all whom it may concern:

Be it known that I, ALFRED APEL, of the city of St. Louis, State of Missouri, have invented a new and original Design for Tops, 5 of which the following is a full, clear, and exact description, reference being had to the accompanying drawings, forming a part hereof.

Figure 1 is a top plan view, and Fig. 2 is a side elevation, of a top embodying my new 10 design.

As shown in the drawings, the leading and material feature of my design consists of the central cylindrical portion having a series of 15 V-shaped parallel grooves formed in its periphery, a portion extending downwardly

from said central cylindrical portion in the form of an inverted cone and having a rounded apex, and a cylindrical portion above the central cylindrical portion, the last-mentioned cylindrical portion being larger in diameter than said central cylindrical portion. 20

I claim—

The design for a top, substantially as herein shown and described.

In testimony whereof I affix my signature 25 in presence of two witnesses.

ALFRED APEL.

Witnesses:

A. McCauley,
S. G. Wells.
